[57] CLAIM

The ornamental design for a test lead, as shown.

DESCRIPTION

FIG. 1 is a perspective view of the test lead according to our new design;

FIG. 2 is a side elevational view thereof;

FIG. 3 is a top plan view thereof;

FIG. 4 is a bottom plan view thereof;

FIG. 5 is an enlarged end view thereof, as seen from the left side of FIG. 2;

FIG. 6 is an enlarged end view thereof, as seen from the right side of FIG. 2;

FIG. 7 is an exploded view of the tip end of FIG. 4, showing the inner construction of the tip; and,

FIG. 8 is a perspective view of another embodiment of the test lead of our new design, the modifications appearing at the connector and tip.
